CLAIM

The ornamental design for an antenna coil housing, as shown and described.

DESCRIPTION

1. Antenna coil housing

1.1 : Perspective

1.2 : Front

1.3 : Bottom view of upper element

1.4 : Top view of lower element

1.5 : Sectional view

1.6 : Sectional view

The broken line showing in figures 1.1, 1.5 and 1.6 is for the purpose of illustrating portions of the antenna coil housing and forms no part of the claimed design.
